US00D768617S

(12) **United States Design Patent** (10) **Patent No.:** **US D768,617 S**
Merenda (45) **Date of Patent:** **** Oct. 11, 2016**

(54) **PROTECTIVE COVER**

(71) Applicant: **HYBRID SKILLZ INC.**, New York, NY (US)

4,942,617 A 7/1990 Boylan
5,422,957 A 6/1995 Cummins
D397,246 S 8/1998 Hoofnagle et al.

(Continued)

(72) Inventor: **John T. Merenda**, New York, NY (US)

(73) Assignee: **HYBRID SKILLZ INC.**, New York, NY (US)

(**) Term: **15 Years**

(21) Appl. No.: **29/550,034**

(22) Filed: **Dec. 30, 2015**

Related U.S. Application Data

(63) Continuation-in-part of application No. 29/481,255, filed on Feb. 3, 2014, now Pat. No. Des. 748,085, which is a continuation-in-part of application No. 29/430,245, filed on Aug. 23, 2012, now Pat. No. Des.

(57) **CLAIM**

The ornamental design for a protective cover, as shown and described.

DESCRIPTION

FIG. 1 is a front perspective view of a protective cover showing my new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof;

FIG. 8 is a front perspective view of a protective cover, showing the second embodiment of my new design;

FIG. 9 is a front elevation view thereof;

FIG. 10 is a rear elevation view thereof;

FIG. 11 is a left side view thereof;

FIG. 12 is a right side view thereof;

FIG. 13 is a top plan view thereof; and,

FIG. 14 is a bottom plan view thereof.

All broken lines depict unclaimed environment and form no part of the claimed design.

1 Claim, 10 Drawing Sheets

Related U.S. Application Data

698,772, and a continuation-in-part of application No. 29/455,255, filed on May 17, 2013, said application No. 29/430,245 is a continuation-in-part of application No. 29/417,184, filed on Mar. 30, 2012, now Pat. No. Des. 667,823.
